CLAIM

The ornamental design for a particle spreader as shown and described.

DESCRIPTION

FIG. 1 is an upper rear perspective view of a particle spreader embodying our design;

FIG. 2 is a lower front perspective view of the particle spreader shown in FIG. 1;

FIG. 3 is a front elevational view of the particle spreader shown in FIGS. 1 and 2;

FIG. 4 is a right side elevational view of the particle spreader shown in FIGS. 1-3, with the left side elevation view being a mirror image thereof;

FIG. 5 is a rear elevational view of the particle spreader shown in FIGS. 1-4;

FIG. 6 is a top view of the particle spreader shown in FIGS. 1-5;

FIG. 7 is a bottom view of the particle spreader shown in FIGS. 1-6;

FIG. 8 is an upper rear perspective view of a particle spreader similar FIG. 1, but with unclaimed portions of the particle spreader being removed;

FIG. 9 is a right side elevational view of the particle spreader similar FIG. 4, but with unclaimed portions of the particle spreader being removed;

FIG. 10 is a front elevational view of the particle spreader similar FIG. 3, but with unclaimed portions of the particle spreader being removed;

FIG. 11 is a rear elevational view of the particle spreader similar FIG. 5, but with unclaimed portions of the particle spreader being removed;

FIG. 12 is a top view of the particle spreader similar FIG. 6, but with unclaimed portions of the particle spreader being removed; and,

FIG. 13 is a bottom view of the particle spreader similar FIG. 7, but with unclaimed portions of the particle spreader being removed.

The broken lines shown in the drawings show portions of the particle spreader that form no part of the claimed design.
